Primary Examiner — Garth Rademaker*Assistant Examiner* — Melvin L Davis(74) *Attorney, Agent, or Firm* — Womble Bond Dickinson (US) LLP(57) **CLAIM**

The ornamental design for a display stand, as shown and described.

DESCRIPTION

FIG. 1 is a topside perspective view of a display stand showing my new design.

FIG. 2 is a bottom side perspective view thereof.

FIG. 3 is another bottom side perspective view thereof with the pedestal shown separated from the tray.

FIG. 4 is a front elevation view thereof.

FIG. 5 is a back elevation view thereof.

FIG. 6 is left side view thereof, with the right side view being a mirror image.

FIG. 7 is a top plan view thereof; and,

FIG. 8 is a bottom plan view thereof.

The broken lines showing candy and pencils in FIG. 1 illustrate environment. All other broken lines illustrate portions of the display stand. None of the broken lines form any part of the claimed design.

1 Claim, 3 Drawing Sheets(56)
